UNITED STATES PATENT OFFICE

2,518,760

AIR-COOLED HEAT EXCHANGER

George H. Dieter, Glendale, Calif., assignor to
The Fluor Corporation, Ltd., Los Angeles, Calif.,
a corporation of California

Application November 13, 1945, Serial No. 627,987

1 Claim. (CL 257—137)

This invention has to do with improvements in heat exchange equipment, particularly condensers for steam or other vapors, in which the condenser units, comprising for example single or multiple banks of tubes, are cooled by fans discharging air against the tubes. Condensers of this type are designed primarily for large capacity outdoor installations, and depending upon the cooling load, for use of multiple blowers capable of directing large quantities of air at 10 high velocity against the condenser tubes.

A principal object of the invention is to provide an improved structure assuring maintenance of the full quantity and velocity of the fan-projected air streams directed against the condenser units. The general structure comprises a vertically extended chamber containing at an intermediate elevation a division or floor which in turn accommodates a fan rotatable about a vertical axis and operating to discharge air taken into the chamber below the floor, upwardly against single or multiple banks of tubes in the top portion of the chamber. The chamber wall structure departs from conventional practices in that the side walls are converged upwardly above the fan to confine and correspondingly increase the velocity of the air stream being projected against the condenser. Specifically, the structure incorporates an outside vertical frame structure spaced from and supporting the side walls, all as will hereinafter appear.

A further object and feature is an improved mounting arrangement of the fan drive parts in a manner permitting convenient access to the prime mover and transmission without interference by the fan, the mounting having the further advantage of independence from the chamber structure in the sense that vibrations in one cannot be transmitted to the other.

The invention and its various features and objects will be understood to better advantage from the following detailed description of the typical and illustrative embodiment shown in the accompanying drawing, in which:

Fig. 1 is a horizontal section taken on line 1—1 of Fig. 2 showing typically a four-cell condenser structure;

Fig. 2 is an enlarged cross-section on line 2—2 of Fig. 1; and

Fig. 3 is a fragmentary section on line 3—3 of Fig. 2 showing the prime mover connection with the transmission.

It will be understood that in any specific embodiment of the invention the air or plenum chamber structure may include one or a plu-

5 rality of individual sections or cells, arranged and provided in total number in accordance with the required cooling capacity of the installation. Merely as illustrative, the drawing shows a four-cell structure, each cell containing its individual fan and with the cells arranged in pairs transversely of the structure.

15 Exteriorly the air chamber 10 and its divisions or cells 11, 12, 13 and 14 are defined by the vertical end walls 15 and the side walls 16. As illustrated in Fig. 2, each side wall includes an upwardly and inwardly inclined section 16a continuing at the top in a substantially vertical section 16b. Below the inclined section 16a the side walls, and also if desired the end walls 15, may include screen 17 or otherwise be of open formation, to permit free induction of air into the bottom portion 10a of the chamber.

20 The chamber 10 contains below the inclined side section 16a a substantially horizontal floor structure 18 above which the chamber is divided into the cells 11 to 14 by the longitudinal and transverse partitions 19 and 20. Below the floor 18, the bottom portion 10a of the chamber is 25 continuous, to permit access from one to the other of the fan driving units. A fan ring 21 is contained in the floor 18 at the bottom of each of the cells 11 to 14, each fan ring being upwardly convergent and extending above the bottom portion of the side wall sections 16a.

30 The described chamber and cell assembly is exteriorly supported by a frame structure and including the vertical columns 22 and beams 23 and 24 extending respectively along and at the outside of the end and side chamber walls 15 and 16. Beams 25 extending longitudinally of the structure between the end beams 24 are attached to the upper portion 16b of each side wall, thus giving the latter direct transverse support by the spaced outside frame structure. One or 35 more banks of condenser tubes may be arranged in the path of the highest velocity air streams in the top reduced width portions of the cells. Typically, lower tube banks 26 having their headers connected to inlet and outlet lines 27 and 28, are shown to extend through the side wall section 16b and to be supported on the lower beams 25. Similar tube banks 29 extending across the top of the chamber are supported on the upper beams 25.

40 Each of the fan rings 21 contains a fan 30 having a drive shaft 31 connected through a flexible coupling 32 with a transmission 33. As illustrated in Fig. 3, a suitable prime mover such as 50 motor 34 drives the fan shaft 31 through the

transmission by way of shaft 35. As will be observed, the motor and transmission for each individual fan have their footings on an individual foundation 36, so that any vibrations occurring in the drive cannot be transmitted to the chamber structure, as would be the case where common foundations are used; and similarly any vibrations occurring in the chamber structure, originating for example in the tube banks 26 or 29, cannot be transmitted to the fan driving units. Each drive shaft 31 extends through an elevated support 37 which may contain both radial and thrust bearings, supported on legs 38 in the manner of a tripod, permitting access to all parts of the drive transmission. Thus with the motors and transmissions at substantially ground level and openly accessible, workmen may enter the chamber 10a for service or repair of those parts without interference by the fans 30 which may continue to operate. Thus the invention is distinguished from the conventional practice of mounting the transmission in elevated position and in such close proximity to the fan, that service or repairs cannot safely be made with the fan continuing in operation.

In operation, air taken in through the screened inlet 17 is discharged upwardly through the cells by the fans 30, the air velocity being progressively increased by the convergence of the side wall 16a, to a maximum reached at the location of the exchangers 26 and 29. Placement of supporting members in the outside frame structure permits unobstructed and free air flow desirable for efficient maintenance of the desired air velocities within the chamber and cells. As will be

understood, heat transfer rates in the exchangers 26 to 29 are increased as a function of the increased air velocity resulting from the convergent wall structure.

I claim:

Heat exchange equipment comprising a housing of upwardly decreasing cross-sectional area having an upwardly and inwardly inclined side, an exterior vertical frame structure spaced from and connected to said inclined side, a horizontally extending wall in said housing, an air inlet in the side of the housing below said wall, a fan rotatable about a vertical axis for discharging air upwardly through an opening in said wall and thence at increasing velocity upwardly along said inclined side to the atmosphere, and a heat exchanger positioned at the top portion of the housing in the path of the increased velocity air stream and supported by said external frame structure at the outside and independently of said inclined side.
